UNITED STATES PATENT OFFICE.

JULES RENÉ BLUM, OF PARIS, FRANCE.

SUCTION DEVICE FOR DUST-REMOVING PNEUMATIC MACHINES.

No. 860,786.

Specification of Letters Patent.

Patented July 23, 1907.

Original application filed April 19, 1906, Serial No. 312,672. Divided and this application filed February 20, 1907.
Serial No. 358,449.

To all whom it may concern:

Be it known that I, JULES RENÉ BLUM, civil engineer, a citizen of France, residing at 49 Boulevard Péreire, Paris, France, have invented new and useful Improvements in Suction Devices for Dust-Removing Pneumatic Machines, of which the following is a specification.

This invention which is a division of the application Serial No. 312,672 filed April 19, 1906, relates to 10 improved suction devices adapted to be used in connection with machines for removing dust from carpets, furniture, curtains, tapestry and the like, and the principal object of the invention is to provide for suction devices occupying a small space though being very efficient.

In the accompanying drawing, Figure 1 is a vertical sectional view of a dust removing pneumatic machine incorporating the improved suction devices, and Fig. 2 is a section taken on line A—A of Fig. 1 and looking 20 towards the left.

The dust removing machine comprises the usual flexible aspiration tube *c* terminated in a metallic suction mouth *o*, a filtering receptacle *A* the walls of which consist of a frame of metallic hoops inclosed 25 in an envelop or shell *B* adapted to permit the air to pass therethrough and at the same time to filter the same, said receptacle being arranged within a hermetically closed box *D* which is immovably secured upon the stationary flap of the upper bellows 1, and 30 the suction devices which will be hereinafter described and claimed. These devices comprise four bellows 1, 2, 3, 4 coupled together in pairs with a movable flap common to each pair. To each flap is jointed a depending link or connecting rod *a* or *b* jointed at 35 its other end to one of the cranks of a two-crank winch driving shaft *c*. Rotary motion is imparted to this shaft either mechanically or by hand.

Each bellows has a suction or inlet valve *i* and an 40 expulsion or outlet valve *j*. All the suction valves open toward a single vertical compartment *k* of the

casing similarly, and all the expulsion valves into a vertical compartment *l*. These two compartments are formed in a flat chamber extending throughout the width of the casing *C* of the machine, a vertical partition *E* being provided for to separate both compartments. This arrangement allows of profiting in the best conditions of all the space available.

The suction compartment *k* is connected with the interior of the filtering receptacle *A*, and the expulsion compartment *l* communicates by an orifice *q* with the 45 interior of the casing *C* of the machine.

The operation of the suction devices can be easily understood: when the movable flaps of the bellows are driven downwards, the bellows 1 and 3 cause the dust-laden air to be sucked through the filtering envelop *B* which retains the dust, and at the same time the bellows 2 and 4 expulse the pure air sucked in the previous stroke; when on the contrary the movable flaps are lifted up, the bellows 2 and 4 produce the 50 suction, while the bellows 1 and 3 assure the expulsion of the pure air.

Having now described my invention, what I claim as new and desire to secure by Letters Patent is:

In a machine for removing dust by suction from carpets, furniture, curtains, tapestry and the like, suction devices 65 comprising in combination, an even number of bellows 1, 2, 3, 4, . . . coupled together in pairs with a movable flap common to each pair, depending links *a*, *b*, . . . connecting the movable flap to the cranks of a winch driving shaft, a suction valve *i* and an expulsion valve *j* provided for in 70 each bellows, a vertical flat compartment *k* into which lead the suction valves *i* and which communicates with the interior of the filtering receptacle *A*, and a vertical flat compartment *l* into which lead the expulsion valves *j* and which forms with the compartment *k* a flat chamber extending throughout the width of the casing *C* of the machine, substantially as described and for the purpose set forth.

In testimony whereof I have signed my name to this specification in the presence of two subscribing witnesses. 80

JULES RENÉ BLUM.
